WINDOW PANE

Robert A. Keyes, Inglewood, Calif., assignor to
LeVan Specialty Company, Inc., Industry, Calif.

Filed Apr. 24, 1973, Ser. No. 354,015

Term of patent 14 years

Int. Cl. D25—02

U.S. Cl. D25—72

FIG. 1.

FIG. 2.

FIG. 1 is a plan view of a window pane showing my new design; and

FIG. 2 is an elevational view of the same.

The rear side of the window pane opposite that shown in FIG. 1 is plain and not ornamented.

I claim:

The ornamental design for a window pane, as shown and described.
